UNITED STATES PATENT OFFICE

2,691,874

ABSORPTION REFRIGERATING APPARATUS

René Martin, Casablanca, Morocco

Application March 27, 1951, Serial No. 217,728

Claims priority, application Morocco
March 30, 1950

2 Claims. (Cl. 62—119.5)

1

The present invention is relative to continuous cycle, absorption type refrigerating apparatus, operating from any heat source (electricity, gas, kerosene).

In apparatus known at present, it is common to note that the heat exchanger is placed adjacent to the boiling element, or, in some cases concentrically thereto, but in these two cases, the emulsifier or thermal pump is not always placed on the central tube of the boiler, or, if so, the thermal contact not being sufficient to give the emulsifier an adequate activity, a small diameter tube is associated with it, which extends it and, being wound around the central tube of the boiler, increases the contact area.

It is common, also, to note, on existing apparatus, that the steam tube, collecting the vapours of the boiler to the condensing element, connects directly said two elements, to allow the water vapours carried away with ammonia vapours to condense, so that only vapours rich in ammonia are allowed into the condenser; there is often added a water separator consisting of a set of inner baffles, and outer cooling fins, a suitable slope making it possible for the condensed water vapour to come back to the boiler.

The present invention covers a continuous cycle, absorption type refrigerating apparatus wherein:

(a) The thermal pump or emulsifier is in direct and intimate contact, by welding, with the boiler tube.

(b) The vapour tube is amply dimensioned and offers, at its lower portion, baffles, for separating the refrigerating medium from its vehicle.

(c) The upper portion of the vapour tube is arranged above the condenser and cooled by the air stream rising from the latter.

(d) The tube forming the coil of the evaporator offers, inside, striations, perpendicular to the direction of flow of the refrigerating medium, for braking it and fractioning it so as to allow its complete combination with the vehicle.

(e) Plates are clamped on the coil of the evaporator, some forming an arch and others forming the ground, so as to constitute compartments wherein are housed ice drawers and possibly the products to be frozen.

One type of embodiment of the object of the invention is represented, by way of example, in the appended drawings.

Figure 1 is a front elevation, partly in section, of the apparatus.

Figure 2 is a side elevation of the apparatus.

Figure 3 is a plane view, partly cut away, of the apparatus.

2

Figure 4 is an enlarged cross-sectional view of the vapour tube and corresponding to line 4—4 of Figure 1.

Figure 5 is a cross-sectional view corresponding to line 5—5 of Figure 4.

In Figure 1, 1 designates the boiler tube, which is heated by any heat source (electricity, gas or kerosene). This tube is extended, at its upper portion, by a vapour tube 2, assuming the shape of a V, the end of which 2a opens into the condenser 3 which is connected by means of the tube 4 with the evaporator 5, placed in the refrigerating cupboard. The tube 4 is extended, upwards, by a return circuit 6, 7 to the absorber 8, which opens at its lower end into a tank 9, connected through a tube 10 with the temperature exchanger 11. The thermal pump 12 is welded except at its upper part (Figure 1) to the base 1a of the boiler 1. To this effect, an intense metal fusion is effected between the body of the boiler 1 and the pump 12. This pump, connected with the temperature exchanger 11 through a tube 13 projects the mixture of the refrigerating medium and its vehicle up to the upper portion 1b of the boiler 1 through the tube 14. The arrangement of the pump 12 with respect to the boiler 1 allows a suitable activity of the latter, since a thermal contact is directly ensured. The vapour tube 2, connected to the upper portion of the boiler tube 1 is amply dimensioned and comprises, at its lower portion, baffles 2b (Figures 4 and 5), while its upper portion, passing above the condenser 3 utilizes, for its cooling, without the use of any fins, the upward forced air stream issuing from the fins of the condenser 3, which ensures it a sufficient cooling. This condenser is a two-stage condenser and is arranged in such a manner that its ventilation be not hindered by the vapour tube 2. Further, the evaporator 5, which is of the coil type, comprises one or more metal plates 16, firmly clamped on to the coil 15. Some of these plates form the ground and others form the arch of compartments wherein are housed ice drawers and possibly the products to be frozen. This arrangement allows a transmission with a perfect thermal conductivity between the coil 15, the plates 16 and the products to be preserved.

There occurs in the evaporator 5, in addition to the evaporation of the refrigerating agent, producing cold, a fractioning and a combination of the agent with the neutral gas which is used as its vehicle, and which is generally hydrogen. This combination should be as complete as possible, and in order that part of this refrigerating agent does not leave the coil in a liquid condition,

the latter comprises inner helical striations 17 (Figure 3). These striations are perpendicular to the direction of flow of the refrigerating agent and consist of a close pitched tapping. The effect of these striations is to brake the flow of the refrigerating agent and to fraction it to allow its combination with the vehicle and thus avoid its leaving the evaporator 5 in a liquid condition to return to the absorbing element 8 before its complete evaporation, which would have the effect of causing a substantial decrease in efficiency of the refrigerating unit.

I claim:

1. A refrigerating apparatus of the absorption type, comprising a heating tube, a boiler arranged concentrically with said tube, a vapor tube issuing from the upper portion of the boiler, said vapor tube with a V-shaped large section, with superposed and substantially horizontal branches starting from the upper portion of the boiler, baffles, placed in the lower branch of said tube, a condenser placed between the two branches of the V-shaped vapor tube and connected with the upper portion of said tube, an evaporator to be placed in the chamber to be refrigerated, an absorber in communication with said evaporator, a tank in which the absorber opens, a heat exchanger comprising two tubes placed concentrically to one another, the outer tube connected with the upper portion of the absorber at one end and at the other end with the under portion of the said boiler, a conduit between the tank and the inner tube of the heat exchanger, a thermal pump welded on the heating tube and arranged in heat conductive relation therewith, said thermal pump being connected at its upper portion with the inner tube of the heat exchanger, said latter being wound in spirals around the lower portion of the heating tube, and a small diameter tube connected with the upper portion of the thermal pump rising along the boiler and connected with the upper portion of said boiler.

2. A refrigerating apparatus of the absorp-

tion type, comprising a heating tube, a boiler arranged concentrically with said tube, a vapor tube issuing from the upper portion of the boiler, said vapor tube with a V-shaped large section, with superposed and substantially horizontal branches starting from the upper portion of the boiler, baffles, placed in the lower branch of said tube, a condenser placed between the two branches of the V-shaped vapor tube and connected with the upper portion of said tube, an evaporator to be placed in the chamber to be refrigerated, an absorber in communication with said evaporator, a tank in which the absorber opens, a heat exchanger comprising two tubes placed concentrically to one another, the outer tube connected with the upper portion of the absorber at one end and at the other end with the under portion of the said boiler, a conduit between the tank and the inner tube of the heat exchanger, a thermal pump welded on the heating tube and arranged in heat conductive relation therewith, said thermal pump having an upper part detached from said heating tube and connected to the inner tube of the heat exchanger, said latter being wound in spirals around the lower portion of the heating tube, and a small diameter tube connected with the detached upper portion of the thermal pump rising along the boiler and connected with the upper portion of said boiler.
